Int. Cl. D14—03

U.S. Cl. D26—14

FIG. 1 is a perspective view of a telephone rest showing my new design, with the rest shown in association with a telephone illustrated in broken lines, with the parts in one position of operation;

FIG. 2 is a top plan view of the telephone rest;

FIG. 3 is a side elevational view of the telephone rest showing the parts thereof in a second position of operation;

FIG. 4 is a front elevational view of the telephone rest with the parts in the position as shown in FIG. 3;

FIG. 5 is a rear elevational view of the telephone rest; and

FIG. 6 is a sectional view taken substantially on the line 6—6 of FIG. 4.

The broken lines are shown for illustrative purposes only.

I claim:

The ornamental design for a telephone rest, substantially as shown and described.
